UNITED STATES PATENT OFFICE

GEORGE G. FLOYD, OF GRANITE, AND CHARLES F. MURRAY, OF CHICAGO, ILLINOIS, ASSIGNEES TO AMERICAN STEEL FOUNDRIES, OF NEW YORK, N.Y., A CORPORATION OF NEW JERSEY.

COLUMN-GUIDE AND BOLSTER CONSTRUCTION FOR CAR-TRUCKS.

No. 895,737.

Specification of Letters Patent. Patented Aug. 11, 1902.

Application filed November 18, 1901. Serial No. 402,652.

To all whom it may concern:

Be it known that we, GEORGE G. FLOYD and CHARLES F. MURRAY, both citizens of the United States, residing, respectively, at 5 Granite, in the county of Madison and State of Illinois, and Chicago, county of Cook, and State of Illinois, have invented certain new and useful Improvements in Column-Guide and Bolster Constructions for Car-Trucks, of 10 which the following is a specification.

The main and principal object of our invention is the improvement of railway car trucks in such a manner that the truck bolster may be readily removed without necessitating that the bolster and spring aperture in each side frame shall have a portion wide enough to permit the withdrawal of whatever part is equipped with the bolster column guides.

20 In the preferred embodiment of our present invention, the bolster aperture in the side frame is straight, having vertical side margins constituting the columns, and the bolster instead of resting directly on the springs, 25 as is usual, is seated in each side frame on a divided or two-part casting forming a combined bolster support and column guide. This casting has a divided wedge-shaped rib, each portion being integral with one of the parts 30 of the casting, whereby the bolster end having a transverse wedge-shaped groove may be fitted over the divided rib, thereby holding the two parts of the casting together and preventing longitudinal shifting or movement of the bolster, because the parts of the casting have guiding lugs or ribs co-acting 35 with the column portions of the side frame. On its under surface the bolster supporting casting may have a plurality of lugs or projections 40 adapted to coöperate with recesses or apertures in the spring cap to hold the portions of the casting together in whole or in part in matched position.

On the accompanying drawings, forming a 45 part of this specification, we have illustrated two desirable embodiments of our invention, and in the various views like reference characters refer to the same parts throughout.

On said drawings—Figure 1 is a side elevation of a portion of a car truck embodying our invention; Fig. 2 is a central vertical cross-section through the upper portion of

the structure shown in Fig. 1, the springs and spring cap being omitted; Fig. 3 is a horizontal section on line 3—3 of Fig. 2 as 55 viewed in the direction indicated by the arrows; Fig. 4 is a horizontal section on line 4—4 of Fig. 2, the bolster being omitted; Fig. 5 is a perspective view of one end of the bolster; Fig. 6 is a perspective view of the 60 divided bolster supporting casting; Fig. 7 is a view similar to Fig. 1 of a modified construction; Fig. 8 is a central vertical cross-section through the upper portion of the construction shown in Fig. 7, the bolster being 65 unsectioned and the springs being omitted; Fig. 9 is a horizontal section on line 9—9 of Fig. 8 as viewed in the direction indicated by the arrows; Fig. 10 is a section on line 10—10 of Fig. 8; Fig. 11 is a perspective 70 view of one end of the bolster; and Fig. 12 is a perspective view of the divided bolster support and column guide.

Each of the car trucks illustrated has a cast metal side frame 20 with a substantially 75 rectangular central spring and bolster opening 21 having vertical sides or margins 22 forming the columns of the side frame. Resting on a spring seat 23 is the usual number of coil compression springs 24 having at their top 80 ends a spring cap 25 joined to the bottom spring cap 26 by the ordinary bolt or rod 27. Seated on the spring cap 25 is a divided combined bolster support and column guide 28, illustrated in perspective in Fig. 6, composed 85 of two parts 29 and 30 each of which has a bottom wall 31 with upstanding walls 32 at its opposite ends, each of which is preferably provided on its outer face with a guiding rib or lug 33. Along one edge of the base 31 of 90 each half of the bolster support casting there is a rib or flange 34, the inner face of which is beveled or inclined, as is clearly illustrated in Fig. 2. The outer faces of the flanges 34 are flat or plane surfaces and are adapted to be 95 brought together against one another, as is indicated in Fig. 2. On its under surface the bottom wall 31 of each part of the divided bolster support has one or more downwardly-extended lugs or projections 35 which are 100 adapted to fit in apertures or recesses of the spring cap 25, as is obvious. The spring cap itself is sufficient to hold the two parts of the divided casting together in the matched re-

lation shown in Fig. 2, but in addition the bolster 36 has across its under surface a wedge-shaped groove 37 adapted to fit over and receive the divided rib of the casting and bear on the opposite inclined surfaces of its companion parts, clearance being provided, as is clearly illustrated, between the bottom of the bolster and the top face of the bottom wall of the casting, and also between the top of the divided wedge-shaped rib composed of the two parts 34 and the inner portion of the groove 37 of the bolster.

It will be apparent that due to the wedge connection between the bolster and the casting the two parts of the latter will be firmly held together, and if any wear occurs between the casting and the bolster, the parts will be worn to a nice seat and fit. To remove the bolster it is merely necessary to jack it up sufficiently so that the springs may be taken out and the divided bolster support lowered sufficiently to free its divided rib from the bolster, whereupon both parts of the casting may be readily removed sidewise, as is obvious, the one part inwardly and the other part outwardly. It is not absolutely necessary that at each end the two-part casting should have a pair of guiding ribs 33, since a rib to co-act with either the inner or the outer surface of the column 22 would be sufficient, provided the construction was the same at both sides of the truck to maintain the bolster in place and prevent its lengthwise shifting. It will be apparent that the spring cap and bolster both act to hold the parts of the bolster supporting casting in matched relation, and that its divided rib 34, 34 by co-acting with the bolster prevents the latter from moving out of place.

The construction shown in Figs. 7 to 12, inclusive, is much like that illustrated in Figs. 1-6 except that the divided bolster supporting and guiding casting 38 has in place of the lugs or projections 35 on its under surface a divided, curved, downwardly-extended flange 39 adapted to fit over the top ends of the springs or the spring cap. The centrally-disposed divided rib 40 has its surface rounded instead of flattened, as is shown in Fig. 2, and the groove 41 of the bolster 42 is made to correspond in shape. The action between the bolster and rib is, nevertheless, that of a wedge and the bolster acts to hold together the two parts of the casting while the rib thereof prevents lengthwise shifting of the bolster. As in the previous construction, the divided casting is equipped at each end with column guide ribs 42, although, as explained above, one rib at each end would suffice.

Our invention is not limited to the exact details of construction shown and described, and for that reason numerous minor mechanical changes may be made in the devices set

forth herein without departure from the substance of our invention.

We claim:

1. As an article of manufacture, a divided bolster support adapted to rest on the springs of a car truck side frame, each part of the support having a rib or flange which unitedly form a single rib when the parts are in matched position, substantially as described.

2. As an article of manufacture, a divided bolster support adapted to rest on the springs of a car truck side frame, each part of the support having a rib or flange which unitedly form a single wedge-shaped rib when the parts are in matched position, substantially as described.

3. As an article of manufacture, a divided bolster support adapted to rest on the springs of a car truck side frame, one or more parts of said support having a guiding rib adapted to co-act with the side frame, and each part of the support having a rib or flange which unitedly form a single rib when the parts of the support are in matched position, substantially as described.

4. As an article of manufacture, a divided bolster support adapted to rest on the springs of a car truck side frame, the parts of said support having means whereby the spring cap of the springs may hold the parts of the support in matched position, substantially as described.

5. In a railway car truck, the combination of a side frame, a bolster, a vertically divided bolster support on which the bolster rests, and means whereby the bolster holds the parts of the bolster support together, substantially as described.

6. In a railway car truck, the combination of a side frame, a bolster, a divided bolster support having guiding lugs co-operating with said side frame and on which the bolster rests, and means whereby the bolster holds the parts of the bolster support together, substantially as described.

7. In a railway car truck, the combination of a side frame, a bolster, one or more springs having a spring cap, and a divided bolster support on which said bolster rests having means co-operating with said spring cap whereby the latter holds the parts of said bolster support together, substantially as described.

8. In a railway car truck, the combination of a side frame, a bolster having a groove, and a divided bolster support having a rib fitting in the groove of the bolster, the division of said support being through said rib, and the bolster holding the parts of the support together by means of the co-operating groove and rib, substantially as described.

9. In a railway car truck, the combination of a side frame, a bolster having a wedge-shaped groove, and a divided bolster support

having a wedge-shaped rib fitting in the groove of the bolster, the division of said support being through said rib, and the bolster holding the parts of the support together by means of the coöperating groove and rib, substantially as described.

10. In a railway car truck, the combination of a side frame, a bolster having a wedge-shaped groove, and a divided bolster support having a wedge-shaped rib fitting in the groove of said bolster, one or more parts of said bolster support having one or more guiding ribs coöperating with the side frame, the division of said support occurring

through said wedge-shaped rib, and the bolster holding the parts of the support together by means of the coöperating wedge-shaped groove and rib, substantially as described. 15
